Ezra Ripley, of Troy N.Y.
assignor to
Chollar, Sage & Dunham, of West Troy, N.Y.
Letters Patent No. 421. Dated Oct. 28. 1851.

The schedule referred to in these Letters Patent and making part of the same.

To all to whom these presents shall come:

Be it known that
I, Ezra Ripley, of Troy, in the county of Rensselaer, and state of New York
have invented or produced a new & original design of cook
stove, which I call the Boston Casket, & I do hereby declare
that the following is a full & exact description of the same,

Des. 421

reference being had to the annexed drawings making a part of this specification, in which fig. 1, is a view of the front plate and fig. 2, a side view of the stove.

The ornamental design of my stove consists in rosettes a, a, in panels on the doors & rays b, b, issuing therefrom, also rays c, c, forming panels on the front plate and rosettes d, d, bead mouldings e, e, and arabesque figures f, f, the whole being combined and arranged as represented.

What I claim as new and desire to secure by Letters Patent is the design of ornamental and configuration of cook stove substantially the same as herein described & represented.
